DESIGN FOR A FURNITURE POST

Jacob C. Garver, Tippecanoe City, Ohio, assignor
to Detroit Cabinet Company, Inc., Tippecanoe
City, Ohio, a corporation of Ohio

Application December 29, 1933, Serial No. 50,250

Term of patent 3½ years

To all whom it may concern:

Be it known that I, JACOB C. GARVER, a citizen of the United States, residing at Tippecanoe City, in the county of Miami and State of Ohio, have invented a new, original, and ornamental Design for a Furniture Post, of which the following is a specification, reference being had to the accompanying drawing, forming a part thereof.

In the drawing:

Figure 1 is an elevation of a furniture post
showing my new design;

Figure 2 is a section on the line 2—2 of Figure 1.

I claim:

The ornamental design for a furniture post,
substantially as shown.

JACOB C. GARVER.
